UNITED STATES PATENT OFFICE

WILLIAM ANDERSON, OF FERNDALE, MICHIGAN

WALL STRUCTURE

Application filed October 17, 1928. Serial No. 313,073.

This invention relates to wall structures and it is an object of the invention to provide a structure of this kind comprising a plurality of separate units or blocks which, when assembled, provide a wall of a double type having an intermediate dead air space whereby the wall affords an effective insulation against temperature changes and also serves effectually to withstand atmospheric conditions, and more especially the passage of moisture from the outside of the wall to the inside thereof.

The invention also has for an object to provide a structure of this kind composed of a plurality of units, said units being constructed in a manner whereby adjacent units effectively interlock and are maintained in desired assembled relation in a manner to prevent any of the units becoming displaced by vibration, undue atmospheric conditions or from any other cause which would have a tendency to create such displacement.

An additional object of the invention is to provide a structure comprising a plurality of coacting units wherein each of the units is provided adjacent opposite ends thereof and above and below its vertical center with means coacting with adjacent units whereby such unit is effectively held within the wall structure and in a manner whereby both the rear and front faces of the wall structure are maintained in desired assembled relation.

A still further object of the invention is to provide a wall of this kind comprising a plurality of units constructed in a manner whereby said units may be laid in the requisite courses without the use of skilled labor and in a manner materially reducing the production costs.

The invention consists in the details of construction and in the combination and arrangement of the several parts of my improved wall structure whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in perspective illustrating a fragment of a wall structure embodying my invention;

Figure 2 is a view in perspective of a type of corner unit comprised in my improved structure;

Figure 3 is a view in perspective of a straight or conventional unit embodied in the structure as herein disclosed;

Figure 4 is a view in top plan of the structure as illustrated in Figure 1;

Figure 5 is a vertical sectional view taken substantially on the line 5—5 of Figure 4;

Figure 6 is a view similar to Figure 4 but in plan of a course adjacent to the course shown in Figure 4.

My improved wall structure as herein disclosed comprises a plurality of straight blocks or units A and B and the corner units C and D.

Each of the units A and B adjacent to its opposite ends is provided with the inwardly disposed lugs 1 and 2, said lugs 1 and 2, however, being disposed at opposite sides of the vertical center of the unit or block when in applied or working position. While the blocks A and B embody the same structural features, it is to be noted, however, that the lugs 1 and 2 of the unit A are reversely related with respect to the similar lugs of a unit B or, in other words, the block A as herein disclosed has the lug 1 below the vertical center and the lug 2 thereabove while in the type of block or unit B the lug 1 is above the vertical center and the lug 2 below the vertical center.

Each of the blocks A and B and its lugs 1 and 2 are integrally formed preferably of a desired cementitious composition and an end face of each of the lugs 1 and 2 at substantially its axial center has formed therewith an upstanding tapered stud or boss 3 while the opposite end face is formed with a pocket or recess 4. An end edge face but

preferably the top longitudinal edge face of the block or unit A or B is provided with an outstanding flange or tenon 5 while the remaining edge faces of the block A or B is formed therealong with the grooves or mortises 6.

The corner unit or block C, as herein disclosed, comprises two perpendicularly related face members 7 and 8, the member 8 being of a length substantially equal to one-half of the length of the face member 7, and at the junction of said members 7 and 8 and at the lower portions thereof is formed the inwardly disposed lug 1' while the outer end 15 portion of the longer plate 7 adjacent to its upper free corner is provided with the inwardly disposed lug 2'. The corner block or unit D embodies the same structural features as the corner block or unit C except 20 that the face members 7 and 8 are reversely related with respect to the corner block or unit C. The marginal edge faces of the blocks C and D are also provided with the flanges or tenons 5' and the grooves or mortises 6'. These lugs 1' and 2' are also provided in their opposed end faces with the outstanding tapered studs or bosses 3' and the pockets or recesses 4'.

In building a wall structure in accordance 30 with an embodiment of my invention the units A, B, C and D in one course are staggered with relation to the corresponding units in the adjacent course or courses in a horizontal direction, while the blocks or 35 units in one face of the completed wall structure are vertically staggered with respect to the adjacent course or courses of blocks or units in the opposite or second face of the wall structure so that no block or unit in 40 one face of the wall structure is in alignment or coincidence with a block or unit of the second face.

As indicated in Figure 1, it is to be noted 45 that in building a structure the blocks or units A and B alternate in a line diagonal to the vertical whereby the requisite assembly and interfitting or interlocking of the various units is permitted, resulting in such units being effectively tied in a manner to withstand vibration, atmospheric pressure or other strains or stresses which would have 50 a tendency to displace such units or blocks and thereby destroy the wall structure.

It is also to be noted that when the blocks 55 are assembled in the wall structure a dead air space is afforded therebetween thus assuring an effective insulation within the structure against outside temperature changes, and it will also be noted that the interfitting of the flanges or tenons 5 and 5' with the grooves or mortises 6 and 6' will prevent passage of moisture from the outside of the wall to the inner surface 60 thereof. This may be further facilitated by

initially applying upon the edge faces of the various blocks a liquid cement.

When the blocks are applied, and as clearly illustrated in the drawings, the lugs 1 and 2 of the blocks or units in one face of the wall structure lap the lugs of the blocks or units in the second face with the studs or bosses 3 and 3' engaging within the pockets or recesses 4 and 4'. No cementing or binding material is interposed in the lapping portions of these lugs and this is of vital importance as by the omission of such binder moisture that may penetrate the units of one face will not be transmitted to the units of the second face.

It is also to be noted that in the assembly a lug 1 or 1' will interlock with a lug 2 or 2' in an adjacent block or unit in a course immediately thereabove or immediately therebelow, thus assuring the blocks being assembled in staggered relation both in a horizontal and in a vertical direction. As particularly illustrated in Figure 1, it is to be noted that the units in one face of the wall structure lap the adjacent horizontal portions of the courses in the second face except, of course, the bottom course which is in the inner face of the wall structure. This bottom course preferably comprises units or blocks E substantially one-half the height 95 of a unit A or B and provided adjacent one end portion with a single inwardly disposed lug 1'.

By having the lugs 1 and 2 positioned above and below the vertical center of an applied block or unit, the interlocking engagement therewith of the blocks or units A in the adjacent course will effectively hold such unit against swinging movement about either its upper or lower longitudinal edge 10 due to the fact that by so spacing the lugs 1 and 2 different radii of movement must be offset.

In a corner wall structure the end units of the courses of the inner wall face are alternately brought into contact with the two angularly related outer face portions and at the same time the end blocks or units of the inner face wall portions alternately butt 11 each other.

To facilitate this assembly the upper longitudinal flange 5 of certain of the units A and B is cut away, as at 9, so that no hindrance or obstruction will be offered to the particular mounting or application of the unit A or B to be disposed thereacross for requisite contact with the adjacent portion of the outer face of the wall structure. It is also to be noted that the end of the unit A or B having contact with the outer face of the wall structure has its flange or tenon 5 eliminated and a sufficient part of the adjacent end portion of the unit A or B may be cut away to assure proper butting of said 125 130

unit A or B with the face member 7 or 8 of a corner unit or block C or D and, furthermore, to assure the proper positioning of a lug 2 of a unit A or B with respect to a lug 2' of a corner unit C or D.

5 By being able to build a wall structure of a hollow or double face type from the units as hereinbefore referred to it is possible that each of the units may be produced or formed 10 in accordance with the well known pouring process or molding which assures the unit or block possessing greater strength and durability than a block which is molded as is now customary by tamping and the like.

15 From the foregoing description it is thought to be obvious that a wall structure constructed in accordance with my invention is particularly well adapted for use by reason of the convenience and facility with 20 which it may be assembled and operated, and it will also be obvious that my invention is susceptible of some change and modification without departing from the principles and spirit thereof and for this reason I do not 25 wish to be understood as limiting myself to the precise arrangement and formation of the several parts herein shown in carrying out my invention in practice except as hereinafter claimed.

30 I claim:—

1. As a new article of manufacture, a block, and lugs extending in the same general direction from the block adjacent to opposite ends thereof, said lugs being offset 35 one with respect to the other in a direction transversely of the block, opposed faces of the lugs being provided with locking means whereby to interlock a block in one wall structure with a plurality of blocks in the 40 opposing wall structure.

2. As a new article of manufacture, a block, and lugs extending in the same general direction from the block adjacent to opposite ends thereof, said lugs being offset 45 one with respect to the other in a direction transversely of the block, a face of each of the lugs being provided with an outstanding boss, the opposed face being provided with a pocket whereby to interlock a block in 50 one wall structure with a plurality of blocks in the opposing wall structure.

3. As a new article of manufacture, a building block for placement in a horizontal tier, a lug extending from the inner face of 55 each end portion of the block, one of said lugs being below the vertical center of the block with the other lug above said vertical center.

4. As a new article of manufacture, a 60 building block for placement in a horizontal tier, a lug extending from the inner face of each end portion of the block, one of said lugs being below the vertical center of the block with the other lug above said vertical 65 center, each of said lugs being of a height

equal to substantially one-half the height of the block.

5. As a new article of manufacture, a building block for placement in a horizontal tier, a lug extending from the inner face of 70 each end portion of the block, one of said lugs being below the vertical center of the block with the other lug above said vertical center, each of said lugs being of a height equal to substantially one-half the height 75 of the block, the opposed faces of each of the lugs being flat.

6. As a new article of manufacture, a building block for placement in a horizontal tier, a lug extending from the inner face 80 of each end portion of the block, one of said lugs being below the vertical center of the block with the other lug above said vertical center, each of said lugs being of a height equal to substantially one-half the height of the block, a face of each of the lugs being provided with an outstanding boss, the opposed face being provided with a pocket.

90 In testimony whereof I hereunto affix my signature.
